UNITED STATES PATENT OFFICE

2,561,191

COMPRESSED AIR CIRCUIT BREAKER WITH
A PLURALITY OF SERIES CONNECTED
BREAKING GAPS

Haakon Forwald, Valhalla, Ludvika, Sweden, assignor to Allmanna Svenska Elektriska Aktiebolaget, Västerås, Sweden, a Swedish corporation

Application January 17, 1948, Serial No. 2,917
In Sweden November 24, 1943

Section 1, Public Law 690, August 8, 1946
Patent expires November 24, 1963

2 Claims. (Cl. 200—148)

1

The present invention relates to a high voltage compressed air circuit breaker with a plurality of series connected breaking gaps, in which the breaking gaps are arranged in extinguishing chambers disposed along a central insulating cylinder column. According to this invention, each extinguishing chamber comprises a breaking gap and an air operating cylinder for the movable contact of the breaking gap. By the arrangement of the contact operating cylinder in the chamber, the chambers may easily be removed from the insulating column for inspection or repair and may be replaced by a spare chamber without disturbing the adjustment of the contacts in the spare chambers. The operating cylinders are fed with operating air from the interior of the column or from a pipeline in it. The operating air is in the first place controlled by a valve for each chamber which valves are actuated by an operating shaft, and in the second place a common control valve is provided for all chambers.

On the accompanying drawing Fig. 1 shows a form of the invention, in which the operation takes place by means of a compressed air pipe line traversing the column and provided with branches to the different breaking gaps. In the form shown in Fig. 2 the operation takes place by means of an insulating shaft in the column, which shaft acts on operating valves for the different breaking gaps.

On the accompanying drawing 1 designates the base plate of a circuit breaker, on which the compressed air container 2 is arranged and on this container rests a column 3 and an insulator 4 for a disconnecting switch arranged outside the circuit breaker. The different breaking gaps are arranged in extinguishing chambers 5, 6 and 7 which by means of metal pipes 8, 9 and 10 are attached to the column 3 which consists of a lower insulator 11 having thereon three further insulating cylinders 12, 13 and 14, which are joined by means of metal joining members 15, 16 and 17. The movable contacts in the extinguishing chambers are designated by 18, 20 and 22 and the stationary contacts by 19, 21 and 23. These contacts are arranged in air escape caps 24, 25 and 26, which are attached to the upper ends of the insulating cylinders 5, 6 and 7. The movable contacts are operated by pistons 27, 28 and 29, which move in operating cylinders 30, 31 and 32, which by pipes 33, 34 and 35 are in communication with a central operating pipe line 36, which extends through the whole central insulating column from the control valve 37 in the

2

base plate. The pipe line 36 is made of pipes of insulating material except on the points where the branching to the different operating cylinders takes place, where T-pieces of metal are inserted. The upper cylinder 14 is closed at its upper end by a cover 38 which is metallically joined with the cap 26 by means of a joining member 39 and the caps 24 and 25 are joined with the metallic members 16 and 17 by means of metallic joining pieces 40 and 41.

The compressed air is delivered to the column 3 and the operating valve 37 through a valve 42 and traverses the column 3 and the metal pipes 8, 9 and 10 to the cylinders 5, 6 and 7. The control valve 37 is a three-way valve so designed that in one position the operating line 36 is put in communication with the external air, and in this case the pressure acting on the upper side of the pistons 27, 28 and 29 will move the pistons downwards so that the breaking gaps are opened. When closing the circuit breaker the valve 37 is changed, so that air from the compressed air container 2 again is delivered to the pipe line 36. Since the pressure on both sides of the pistons 27, 28 and 29 will be equal, they will be returned to the position, where the contacts are closed due to the action of the springs 43, 44 and 45. The disconnecting switch, which consists of the disconnecting switch arm 46 with its counter contact 47, is operated by the operating insulating shaft 48.

The form shown in Fig. 2 differs from the above only in that the delivery of compressed air to the different operating cylinders takes place by means of valves 58, 59 and 60, which are operated by an insulating shaft 51, driven by an operating mechanism 52. The operating valves 58, 59 and 60 are so designed that in one position compressed air from the valve 42 is delivered to the pipe lines 33, 34 and 35, whereas in another position these lines are brought in direct communication with the external air at the points 53, 54 and 55.

I claim as my invention:

45 1. A high tension compressed air circuit breaker comprising a central column of insulating cylinders, joining members between said insulating cylinders, a compressed air container, a pipeline between said air container and said 50 insulating cylinder column, an extinguishing valve in said pipeline, extinguishing air chambers comprising movable contacts and stationary contacts laterally and dismountably secured to said column, hollow connecting members connecting the interior of said extinguishing cham-

bers with the interior of said insulating column, contact operating cylinders in said extinguishing air chambers, contact operating pistons in said cylinders, a contact operating air pipeline in said column, pipes joining said operating cylinders with said operating air pipeline, and a contact operating air valve in said operating air pipeline.

2. A high tension compressed air circuit breaker comprising a central column of insulating cylinders, joining members between said insulating cylinders, a compressed air container, a pipeline between said air container and said insulating cylinder column, an extinguishing valve in said pipeline, extinguishing chambers comprising movable contacts and stationary contacts laterally and dismountably secured to said column, hollow connecting members connecting the interior of said extinguishing chambers with the interior of said insulating column, contact 20

operating cylinders in said extinguishing chambers, contact operating pistons in said cylinders, an operating shaft in said column, a driving device for said shaft, contact operating air valves actuated by said shaft, and pipes joining the interior of said contact operating cylinders with the interior of said column through said operating air valves.

HAAKON FORWALD.
